UNITED STATES PATENT OFFICE.

MARX HOLT, OF CHICAGO, ILLINOIS.

TABULAR SUBFILING FOLDER.

1,378,959.

Specification of Letters Patent.

Patented May 24, 1921.

Application filed May 9, 1919. Serial No. 296,033.

To all whom it may concern:

Be it known that I, MARX HOLT, a citizen of the United States, residing at Chicago, county of Cook, State of Illinois, have invented certain new and useful Improvements in Tabular Subfiling Folders, and declare the following to be a full, clear, and exact description of the same, such as will enable others skilled in the art to which it pertains to make and use the same, reference being had to the accompanying drawings which form a part of this specification.

My invention has for its object to produce a simple and novel device in the form of a folder such as employed in the vertical filing of letters of usual or cap size, containing a large number of pockets adapted to hold cards or slips preferably in such relation to each other as automatically to tabulate and present to the eye in organized form the data carried by the cards or slips.

The various features of novelty whereby my invention is characterized will herein-after be pointed out with particularity in the claims; but, for a full understanding of my invention and of its object and advantages, reference may be had to the following detailed description taken in connection with the accompanying drawing, wherein:

30 Figure 1 is a plan view of a folder, open so as to lie flat, having on one of the leaves or sections a plat of pockets some of which contain cards or slips;

35 Fig. 2 is a section on an enlarged scale showing a fragment of the folder, taken on line 2—2 of Fig. 1;

Fig. 3 is a section on an enlarged scale taken approximately on line 3—3 of Fig. 1, only a fragment of the folder being shown;

40 Fig. 4 is a plan view of the blank which is folded to produce the pockets, a portion of the blank being broken away; and

Fig. 5 is a perspective view of a partially opened folder, containing two plats of 45 pockets, one on each half or leaf of the folder.

Referring to Figs. 1 to 4 of the drawing, 1 and 2 are the two leaves or halves of a folder which may conveniently be one of the 50 commonly used folders of heavy Manila paper large enough to receive letter paper or legal cap paper. The inner side of the member 1 is covered with a series of pockets so disposed that slips or cards may be inserted in directions at right angles to the hinge or fold. In order to read the data on

the slips or cards, 3, in the pockets, the folder must therefore be held with the fold or hinge horizontal, namely in the position which it occupies in the ordinary filing cabinet. 60

The pockets are formed by means of a single sheet of strong paper or other suitable flexible material, folded in plaits and stitched across at intervals at right angles to the direction of the plaits. 65

In Fig. 4 there is illustrated a sheet, 4, properly shaped and creased for the intended purpose. Referring to this figure, the dotted line, 5, represents a crease along which the sheet is adapted to be folded, the fold along the line 5 forming the bottom of the upper row of pockets. The dotted line, 6, represents a crease or a line along which the second fold in the sheet is to be made; the panel between the lines 5 and 6 forming 75 the inner thickness of the front wall of the uppermost row of pockets, and the fold along the line 6 forming the upper free edge of the upper row of pockets, such edge being indicated at 60 in Fig. 1. The line 7 represents the third crease or line of fold from the top; the fold along this line forming the bottoms of the second row of pockets from the top. The dotted line, 8, represents a crease or line of fold bearing the same relation to 85 the line 7 as the line 6 bears with respect to the line 5; the fold on the line 8 forming the upper free edge of the second row of pockets, as indicated at 80 in Fig. 1. The sheet is creased in this way throughout its entire 90 length to produce the desired number of pockets. At each end of the panel or section lying between the creases 6 and 7 and all corresponding panels or sections, is a projecting tab, 10, having a width in the direction of 95 the length of the sheet preferably equal to the distance between the upper edges of adjacent rows of pockets in the completed device; that is, equal to the distance between the edges 60 and 80 in Fig. 1, for example. 100 It will thus be seen that when the sheet is folded along the line 5 and then folded in the reverse direction along the line 6 so that the panel or section between the lines 6 and 7 overlies the panel or section between the 105 lines 5 and 6 and a corresponding area in the sheet above the line 5, the tabs, 10, may be folded around the edge of the sheet and, when pasted or glued to the rear side, will close the ends of the upper single long pocket 110 extending entirely across the sheet. Then, when the sheet is again folded along the line

7 and reversely folded along the line 8, the next set of tabs is brought close up to the first set and, when folded around to the back side of the sheet and fastened there by gluing or pasting, completes the closure of the ends of the uppermost long pocket and at the same time closes the upper ends of the second long pocket. In this way, when the entire sheet has been folded into pockets, the tabs 10 form, in effect, a continuous binding from one end to the other; each of the panels or sections corresponding to that between the lines 6 and 7 being made sufficiently wider than the panels or sections corresponding to 15 that between the lines 5 and 6, to bring about this particular relation between the tabs.

After the sheet has been folded or plaited it is stitched along lines at right angles to the creases or folds as indicated at 11, in order 20 to divide each long pocket into any desired number of short pockets. The completed plat is then fastened to the inner side of one of the leaves of the folder, preferably by means of glue or paste.

25 In Figs. 2 and 3 I have illustrated, in sections taken at right angles to each other, in an exaggerated form, the construction of the completed device; the pockets being indicated at 12. It will be seen that the exposed 30 or front wall of each pocket is made up of two thicknesses or layers of material, as indicated at 13 and 14; thus producing a strong, substantial structure.

In the arrangement shown in Fig. 5 there 35 is a plat of pockets, 15, similar to the one just described while on the other half of the folder is a second plat having pockets arranged at right angles to the pockets in the plat 15, so that the folder must be held with 40 the fold or hinge vertical or extending at right angles from the observer, in order to bring the pockets into an upright position. The pockets in the plat 16, furthermore, are 45 larger than those in the other plat. However, the arrangement shown in Fig. 5 is simply intended to be illustrative of one of

many modifications that may be made, as it will of course be understood that the size and disposition of the pockets, and the relative arrangement on both sides of the folder, if both sides are utilized, is a matter of choice, depending upon the use to which the device is to be put. 50

While I have illustrated and described with particularity only a single preferred 55 form of my invention, I do not desire to be limited to the exact structural details thus illustrated and described; but intend to cover all forms and arrangements which come within the terms employed in the definitions of my invention constituting the appended claims. 60

I claim:

1. A device of the character described, comprising a paper filing folder for vertical 65 filing, and plats of pockets secured to the inner faces of both of the leaves of the folder, said plats being formed of thin tough paper plaited and stitched transversely to the plaits. 70

2. A device of the character described, comprising a filing folder and a plat of 75 pockets secured to the inner face of each of the leaves of the folder, the pockets in each plat being arranged in rows, the mouths of the pockets in each row in one plat being parallel with the hinge or fold of the folder, and the mouths of the pockets in the other plat being arranged at right angles to said hinge or fold. 80

3. A plat of pockets made out of a single sheet of flexible material folded into plaits and having oppositely projecting tabs at intervals folded around the edges of the plaited sheet and having their free ends secured by pasting, whereby there is formed a series of pockets closed at the ends by said tabs. 85

In testimony whereof, I sign this specification.

MARX HOLT.
